Inventor

JOHN J. McINTYRE,

BY

R. L. Berry

Attorney

UNITED STATES PATENT OFFICE.

JOHN J. MCINTYRE, OF LOS ANGELES, CALIFORNIA.

HINGE.

Application filed October 3, 1922. Serial No. 592,119.

To all whom it may concern:

Be it known that I, JOHN J. MCINTYRE, a citizen of the United States, residing at Los Angeles, in the county of Los Angeles and State of California, have invented new and useful Improvements in a Hinge, of which the following is a specification.

My invention relates to hinges and consists of the novel features herein shown, described and claimed.

My object is to make an improved hinge for mounting windows so that the windows cannot be opened from the outside.

The drawings illustrate the invention.

Figure 1 is a fragmentary sectional perspective showing a window mounted by using my improved hinge.

Figure 2 is a view in elevation of the hinge removed from the window and showing the window leaf up, as when the window is unlocked so as to open to the inside, and looking in the direction of the arrow 2 in Figure 3.

Figure 3 is an edge view looking in the direction of the arrow 3 in Figure 2.

Figure 4 is a perspective of the window leaf.

Figure 5 is a perspective of the casing leaf.

Figure 6 is a fragmentary horizontal section on the line 6—6 of Figure 4.

Figure 7 is a fragmentary horizontal section on the line 7—7 of Figure 1 and looking downwardly.

The window sill 1 has an inner abutment 2 with an outer vertical stop face 3 and an outwardly sloping ledge 4. The casing 5 extends upwardly from the sill 1. The window 6 is connected to the casing 5 by a sliding hinge 7 and my improved hinge 8 and when the window is closed the lower stile 9 fits against the stop 3 and cannot be opened from the outside.

The details of the hinge 8 are as follows:

The window leaf comprises the attaching plate 10, the bearings 11 and 12 rolled from the corners of the attaching plate and extending away from the window, the cam flange 13 extending from the edge of the attaching plate 10 between the bearings 11 and 12 and having an angled cam slot 14, the hinge pin 15 extending through the bearing 11 and screwed into the sleeve 12, the bearing 16 slidably mounted upon the hinge pin 15, the lever 17 pivotally connected to the sliding sleeve, and the cam pin

18 fixed in the lever 17 and sliding in the cam slot 14.

The slot 14 is formed to have oppositely inclined end portions projecting above and below the horizontal to permit the cam pin 18 to move toward and away from the hinge pin 15 on rocking the lever 17 on its pivotal connection on the sleeve 16, and also serves as a means for holding the lever 17 against free movement when in either its upwardly or downwardly extending positions and thereby lock the window in a raised or lowered position.

The casing leaf comprises the attaching plate 19 and the bearings 20 and 21 rolled from the central portion of one edge in a direction towards the window and in the opposite direction from the rolling of the bearings 11 and 12. The parts are assembled by placing the bearings 20 and 21 between the bearings 11 and 12 with the bearing 16 between the bearings 20 and 21 and then inserting the hinge pin 15. The outer end of the lever 17 extends beyond the cam flange 13 and serves as a handle. When the lever is disposed in an upwardly extending position as shown in Figure 3, with the cam pin 18 located in the upper end of the cam slot, the window to which the leaf 10 of the hinge is attached will be disposed in an elevated position clear of the stop 3 so that the window may be swung inwardly. The inclined upper margin of the slot 14 engaging the pin 18 will, in exerting a side-wise thrust on the pin 18, serve to maintain the lever 17 in its upwardly extending position and thereby support the window in its uppermost position. When it is desired to move the window downwardly after it has been swung to its closed position, the lever 17 is moved downwardly, which permits the hinge leaf 10 and the window supported thereon to move downwardly therewith; the pin 18 riding outwardly in the slot 14 as the lever moves downwardly on its pivotal connection with the sleeve 16 until the pin and sleeve are in horizontal alignment; whereupon, upon continued downward movement of the lever 17 the pin 18 will ride into the lower inclined portion of the slot 14 and into the position shown in Figure 1. The lever 17 will then be disposed in a downwardly inclined position with the pin 18 located at the lower end of the slot 14, which automatically locks the window against the ledge 4 outside of the stop 3 so

that the window cannot be opened from the outside. The hinges are upon the inside of the window and the window must swing inwardly to open. When it is desired to open 5 the window the handle end of the lever 17 is raised to a horizontal position thus elevating the cam pin 18 to a position intermediate the ends of the slot which releases the window so that it may then be lifted above the 10 stop 3 and swung inwardly. On lifting the window the pin 18 will move into the upwardly inclined portion of the slot 14 and when seated in the upper end of the slot, the window will be locked in its elevated position. 15 The hinge 7 allows the window to slide up and down as required to operate the hinge 8 and of course the window opening is designed to allow of the operation.

Various changes may be made without departing from the spirit of my invention as 20 claimed.

I claim—

1. A hinge comprising a window leaf having an attaching plate with bearings at op-

posite corners, a slotted cam flange extending 25 from the attaching plate between the bearings, a hinge pin in the bearings, a sleeve on the hinge pin, a lever pivoted to the sliding sleeve and having a cam pin extending into the cam slot and extending 30 beyond the cam flange to serve as a handle, and a casing leaf having bearings fitting upon the hinge pin on each side of the sliding sleeve; said pin being slidable in said 35 bearings and sleeve.

2. A hinge comprising a leaf, a hinge pin carried on said leaf and held against longitudinal movement thereon, a sleeve on said pin, a lever pivoted on said sleeve, a cam flange on said leaf formed with an 40 angled slot, a pin on said lever slidably engaging said slot, a second leaf, and bearings on said last named leaf encompassing said hinge pin, said bearings being located on opposite sides on said sleeve said pin being 45 slidable longitudinally through said bearings and sleeve and turnable therein.

JOHN J. McINTYRE.
